ROAD WORKING MACHINE

James E. Carlson, Minneapolis, Minn.

Application January 30, 1932. Serial No. 589,911

6 Claims. (CL. 37—152)

This invention relates to road working machinery and the primary object is to provide a highly efficient, practical, and novel design of machine for grading and maintaining gravel and dirt roads. A further or more specific object is to provide a drag frame for attachment behind a tractor, or other power unit, and having a cutting unit for optional engagement with the road surface to plane off corrugations and other irregularities, together with novel means for mounting and adjusting the unit. A further object is to provide a drag frame with trowelling means and supporting wheels with means for adjusting the same whereby said supporting wheels may be used to either support the entire machine, or to partly take up some of the weight thereof when it is desired to have the trowelling means exert relatively less downward pressure on the road material being worked upon. These and other more detailed and specific objects will be disclosed in the course of the following specification, reference being had to the accompanying drawings, in which—

Fig. 1 is a perspective view of the machine showing it as hitched behind a tractor.

Fig. 2 is a plan view of the machine, with fractional parts thereof broken away for purpose of illustration.

Fig. 3 is a sectional elevation as on the line 3—3 in Fig. 2, but with the ground wheels in a position to carry the entire weight of the machine.

Fig. 4 is an end elevation of the machine as seen from the right in Fig. 1, the ground wheels, in this instance, being entirely raised from the road surface.

Fig. 5 is an enlarged detail sectional elevation on the line 5—5 in Fig. 4.

Fig. 6 is a sectional detail view on the line 6—6 in Fig. 5.

Referring to the drawings more particularly and by reference characters, A and B respectively designate front and rear trowelling beams, each of which is made up of an angle iron 7, a trowelling shoe 8, a space bar 9 and a vertical front plate 10, all rigidly secured together. The members 8—9 of each beam are obliquely slanted or beveled off, as at 11, so that as the beams are moved over the road they will not have a scraping or cutting action, as with a conventional drag or scraper blade, but will merely ride over and smoothen down the unevenly distributed relatively loose material. When the beams meet with unusually heavy quantities of loose material they will also serve to effect a distributing

action, under the weight of the machine which is carried on the beams, and the spreading tendencies of the blades or plates 10. It may also be noted that the bevels 11 are so designed that they will permit stones of a predetermined size 60 to pass under the beams and be pressed thereby into the road surface, but that the larger and more undesirable stones will not pass under the beams but will be propelled along by the plates until they ultimately find their way out to one 65 side of the machine.

It may here be noted that the forward trowelling beam is provided with a cutting blade 12 which is preferably adjustable and removable, as disclosed in my co-pending application Serial 70 No. 525,383, filed March 26th, 1931, for Road grader. It may here further be explained that the present application discloses a number of other features which are common to those disclosed in the aforesaid application, as well as being common to certain features disclosed in my co-pending application Serial No. 589,912, filed January 30th, 1932, for Road machine, and to the extent that such features are disclosed in said earlier applications the present application 80 may be considered as a continuation in part thereof.

Referring again to the present disclosure it will be seen that the two trowelling beams, A and B, are rigidly connected by a pair of heavy 85 cast housings or hollow yokes C and D, which are bolted to the beams, as at 13, and are provided, at their forward ends, with brackets 14 to which the ends of a draft chain 15 may be adjustably secured. This chain has an intermediate forward connection with the drawbar 16 of a tractor T, and can obviously be attached so that the machine can be drawn along at any desired angle with respect to the line of draft. For road planning purposes the machine is preferably drawn 95 with the beams A and B in a directly transverse position across the road, but when used for trowelling only the machine is most efficient when operating at a slight angle to such position, and to that end the beams A and B, as well as the planer beam unit E, are offset, as shown in Fig. 2, with respect to each other so that they may properly follow each other when operated at such angle.

The planer unit E comprises a channel iron beam 17 to which are attached, as by bracket 105 plates 18, a plurality of planer blades 19. These blades, as shown, are arranged in oppositely oblique series, as in my application Serial No. 525,383, but are angularly disposed with respect to the perpendicular and otherwise more accu- 110

rately follow the design of blade as shown in my application Serial No. 589,912 to which attention is directed for a more detailed explanation of the function and advantages of the blade arrangement shown.

The beam 17 is rigidly secured, as at 20, to the rear ends of heavy cast levers or arms 21, which are movable upwardly into the forward ends of the beams C and D, and have their forward ends, 10 pivotally attached thereto as at 22. The arms 21 are simultaneously raised and lowered by reversely threaded bars 23 which are pivotally connected to the arms 21 as at 24. These bars have threaded engagement with bevel gears 25 contained within chambers formed by casings 26 attached to the housings C and D. The gears 25 are in turn engaged by bevel pinions 27 carried on the opposite ends of a shaft 28 having a hand wheel 29. Thus it will be seen that the beam 17 15 may be raised and lowered and set in any desired position with respect to the beams A and B, by manipulating the hand wheel 29.

The machine is supported and carried, when not in active use, upon a set of three caster wheels 20 30, 31, and 32, the first of which has a shank 33 25 for swivelling engagement with a bearing member 34 in the forward apex end of a V-shaped frame 35, the rear ends of which are pivotally anchored as at 36 to the rear ends of the housings C and D.

30 The caster 30 is moved into and out of supporting engagement with the ground by vertically adjusting the forward end of the frame 35 with respect to the forward part of the approximately rectangular frame or unit A—B—C—D. These 35 adjustments are effected by the following described mechanism. A threaded, vertically disposed shaft 37 is connected at its lower end to the beam A by a connector 38 permitting swiveling as well as tilting action of the shaft. The 40 shaft 37 operates in a pair of large nuts 39 which are non-rotatably secured in a pair of channel members secured back to back to form a cross bar 40, which cross bar is supported by a pair of coil springs 41 on a second cross bar, 42, secured to the frame 35 as by U-bolts 43. A pair of tie bolts 44 form a further and restricting connection between the bars 40 and 42, and to retain the cross bar 40 in proper position, i. e., to prevent it from 45 turning with the shaft 37, the frame 25 is provided with a pair of upstanding fingers 45 for guiding engagement with the ends of the bar 40. From the foregoing construction it will be seen that the weight of the front portion of the trowelling frame may be carried under spring suspension by the caster wheel 30, or the caster wheel 50 may in turn be carried with the frame 35 by the trowelling frame, by rotating the shaft 37 until the desired adjustment is had. Likewise it will 55 also be noted that through the same mechanism and by similar adjustments the wheel 30 may be adjusted so as to partially relieve some of the weight on the forward trowelling beam, as may be found desirable to do under certain circumstances.

60 The shaft 37 may be rotated to effect the foregoing noted adjustments in various ways, but I find it practical to employ a device for this purpose such as shown and which includes an endless adjuster chain 46, which passes around a 70 sprocket gear 47 on the upper end of the shaft 37, thence forwardly over a pair of pulleys 48 at the upper end of a standard 49, on the tractor, and under a pulley 50 connected to the tractor platform 51 by a spring 52. Thus the operator

of the tractor, sitting on the seat 53 or standing on the platform 51, can rotate the shaft 37 in either direction, to effect the desired adjustments, by pulling on one side or the other of the chain 46. The spring 52 will of course compensate for 80 differences in movements as between the tractor and the machine being drawn, and will insure the retention of the chain in a taut condition at all times. It may here be noted that the chain 46 preferably operates in a tubular or curved 85 guide 54, extending around the sprocket wheel 47. This guide prevents disengagement of the chain 46 with respect to the gear 47, and must of course be rotatably supported with respect to the members 37 and 47.

90 The trowelling beam B, or the rear end of the machine, is raised and lowered with respect to the caster wheels 31, in conjunction with the adjustments of the beam A with respect to caster 30, by mechanisms now to be described.

95 Rotatably mounted in the rear ends of the housings C and D are a pair of threaded shafts 55, the upper ends of which project through bearing caps 56 and are provided with sprocket gears 57. These gears are engaged by a triangularly arranged endless chain 58, a forward portion of which also extends about a sprocket gear 59 on the shaft 37, with a result that when the shaft 37 is rotated it will simultaneously and correspondingly rotate the two shafts 55.

100 To insure retention of the chain 58 in proper operative position with respect to the gears 57 and 59, and to protect it from the elements, I provide guide pipes 67, through which the chain is passed, and which are suitably supported as by 110 end brackets 68.

105 The shafts 55 are held against vertical movements in the casings C and D, but operate in collars 60 (Fig. 3) which are subject to vertical adjustments, on the shafts, when the latter are 115 rotated. These collars 60 are pivotally connected to levers 61 the forward ends of which have freedom for a limited vertical movement in slots 62 of inner housing walls 63. Said forward lever ends are held yieldably upward in the slots 62 120 under the action of springs 64 acting on draw bolts 65 having adjuster nuts 66 for adjusting the tension of the springs.

125 The rear ends of the levers 61 are forked or bifurcated to engage between laterally projecting lugs of blocks 69, which are slidable on vertically disposed shafts 70 rigidly mounted in rearward extensions 71 of the housing units C and D. The blocks 69 operate between upper and lower bearings 72 of the yokes 73 which carry the caster 130 wheels 31 and 32. Thus it will be seen that when the shafts 70 are rotated they will operate through the elements 60—61, 69—70, and 73, to move the casters 31—32 into and out of supporting engagement with the ground; and, also, when the 135 casters are supporting the machine, as in Fig. 3, the springs 64 will take up jars and vibrations imparted thereto by irregularities in the road surface.

140 It will also be noted that the extensions 71 extend sufficiently far back so that the casters 31—32 may be swung to a right angular position with respect to that shown in Figs. 1 and 2, the purpose being to provide means whereby the machine may be drawn in the direction of its transverse length, 145 thus taking up considerably less road space when being transported from one location to another. In this event the left end of the chain 15 is detached from its bracket 14 and is attached to some convenient part of the machine, such as an 150

eye 74, and the machine is then arranged longitudinally with and attached behind the tractor.

The operation and use of the machine may be briefly explained as follows: When being transported from one location to another the machine is carried on the caster wheels 30, 31, and 32, as shown in Fig. 3. The machine may be drawn in the transverse position behind the tractor, as indicated in Fig. 1, or as immediately above described. The ends of the chain 15 can be attached to the right bracket 14 and to the eye 74 so that the machine can be drawn in a longitudinal position behind the tractor. When the machine is to be converted into operative use it must of course be drawn in the direction as shown in Fig. 1, and in this case the operator pulls upon the proper side of the chain 46 until the vertical threaded shafts 37 and 55 have been rotated to effect the necessary lifting of the caster wheels 20 until the shoe plates 8 of the trowelling beams A and B are in supporting contact with the road surface.

If the machine is to be used for trowelling purposes only then the planer unit E is carried in the raised position shown in Fig. 3, and unless it is desired to place some of the weight on the caster wheels 30—31, and 32, the trowelling unit will carry the entire weight of the machine so that as they are pulled forwardly over the road surface they will tend to exert a trowelling action upon the loose material and will smoothen and press it down uniformly throughout the width of the road. The inclined surfaces or bevels 11 have a tendency to move the earth under the trowelling shoes 8 as the machine moves forward, but in the event that either one of the beams A or B meets with an unusually large volume of loose road material it will have a tendency to carry that material forwardly and spread it into the relatively lower parts of the road. The scraper blade 12 may or may not be used, as circumstances may require, but when in use will have a tendency to cut away sharp irregularities in the road surface before such surface is traversed by the respective trowelling beams. It may also be noted that while the trowelling beams are so designed that they will permit small rocks and stones to pass under the beams, larger obstacles such as boulders and large stones will contact with the plates 10 and will be pushed along in front of such plates until they gradually find their way out to one side of the machine.

When the planer unit is to be used the operator turns the hand wheel 29 to rotate the bevel gears 25, thus lowering the threaded bars 23 until the blades 19 have been adjusted to the proper working depth in the road surface. As the machine now moves forwardly the blades 19, due to their peculiar angular positions with respect to the line of draft and also with respect to the perpendicular, engage the road to effect a slicing or planing action in a horizontal plane, and when so operating will cut away the ridges and corrugations in the road surfaces but will do so without shifting the cut material to one side or the other of the road as is done with the con-

ventional grader blade. With the use of this arrangement of planer blades the high spots are shaved or planed from the road and are left in the form of loose material directly behind the respective blades, and this material is trowelled down and smoothed over by the trowelling beam B in the manner first above set forth.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A road machine comprising a frame, a pair of trowelling beams and a road planing device carried by the frame, three spaced ground engaging caster wheels adapted to carry the entire frame, and means for simultaneously raising the caster wheels out of supporting engagement with the road. 90
2. A road machine of the character described comprising a pair of trowelling beams connected by chambered housings, a planer unit disposed between the trowelling beams, and bracket arms 100 movable upwardly into said housings for mounting the planer unit with respect to the trowelling beams.
3. A road machine comprising a main frame having road working elements secured thereto, 105 vertically adjustable caster wheels supporting the rear end of the frame, a secondary frame secured to and vertically adjustable with respect to the main frame, and a ground wheel secured to the secondary frame adjacent the front of 110 the main frame.
4. A road machine comprising a main frame having road working elements secured thereto, vertically adjustable wheels supporting the rear end of the frame, a secondary frame secured to 115 and vertically adjustable with respect to the main frame, and a ground wheel secured to the secondary frame adjacent the front of the main frame, all of said wheels being swingable on vertical axes so as to have caster actions. 120
5. A road machine comprising a main frame having road working elements secured thereto, vertically adjustable caster wheels supporting the rear end of the frame, a secondary frame secured to and vertically adjustable with respect 125 to the main frame, a ground wheel attached to the secondary frame at the forward end of the machine, and shock absorbing devices operatively connecting the rear wheels and said main frame. 130
6. A road machine adapted to be drawn behind a tractor and comprising a frame, road working apparatus carried by the frame, wheels adapted for adjustment so as to carry or be carried by the frame, a draft device for connecting 135 the machine to the tractor, and means extending from the machine for operation by the tractor operator to vertically adjust the said wheels with respect to the main frame, said means comprising an endless flexible element. 140

JAMES E. CARLSON.
